UNITED STATES PATENT OFFICE.

JOSEPH N. MAHONEY, OF WILKINSBURG, PENNSYLVANIA, ASSIGNOR TO WEST-
INGHOUSE ELECTRIC AND MANUFACTURING COMPANY, A CORPORATION OF
PENNSYLVANIA.

CIRCUIT-INTERRUPTER.

1,323,300.

Specification of Letters Patent.

Patented Dec. 2, 1919.

Application filed January 4, 1916. Serial No. 70,266.

To all whom it may concern:

Be it known that I, JOSEPH N. MAHONEY, a citizen of the United States, and a resident of Wilkinsburg, in the county of Allegheny and State of Pennsylvania, have invented a new and useful Improvement in Circuit-Interrupters, of which the following is a specification.

My invention relates to circuit interrupters and particularly to terminals and contact members for such devices.

The object of my invention is to provide terminals and contact members for circuit interrupters that shall be cheap to construct, 15 easily adjusted and assembled and reliable in operation.

My Patent No. 1,224,186, dated May 1, 1917, discloses a circuit interrupter having contact members that are self alining and initially tensioned. However, no means is provided for easily assembling and adjusting the initial relative positions of the contact members.

My present invention utilizes the self alining and the initial tensioning devices set forth in the above mentioned application, but further provides a construction that is relatively cheaper to manufacture and has the additional feature of permitting 30 accurate positioning of the contact members in both horizontal and vertical planes with respect to each other.

Figure 1 of the accompanying drawing is a side elevational view of portions of a circuit interrupter embodying my invention; Fig. 2 is a fragmentary end elevational view of the device shown in Fig. 1, and Fig. 3 is a detail view of a flanged-positioning device embodied in my invention.

40 A circuit interrupter constructed in accordance with my invention comprises a frame 1, stationary switch members 2, an operating rod 3 and a bridging member 4 that is provided with main and auxiliary 45 contact members 5 and 6, respectively.

The bridging member 4 is so shaped that the contact members 5 lie in a plane that is substantially transverse to its axis, and the auxiliary contact members 6 constitute 50 movable bolts that are secured to projections 7 on the ends of the bridging member. The bridging member 4 is adapted to be actuated through the rod 3 by any suitable type of operating mechanism (not shown).

55 The stationary switch members 2 sev-

erally comprise a conducting rod 8, an insulator 9 surrounding the same, a base member 10 that is secured to the lower end of the rod 8, a main stationary contact member 11 and an auxiliary stationary contact member 12. 60 The rod 8 is screw threaded near its respective ends and is adapted to be adjustably secured in any desired position with respect to the insulator 9 by means of nuts 13 and 14 and washers 15 and 16. Thus, the relative position of the contact members may be adjusted. That is, each stationary switch member may be adjusted in a vertical plane independently of the other to obtain more nearly simultaneous engagement of the respective contact members.

The base member 10 is of substantially L-shape, one of its arms being secured to the lower end of the rod 8 and its other arm being provided with an opening in 75 which is disposed a bolt 17 that is provided with a nut 17^a for securing the contact members 11 and 12 thereto. The main stationary contact member 11 is substantially 80 a parallelepipedon in shape having an upper portion cut away. To the lower portion of the contact member 11 is fastened a substantially flat resilient conductor 18 having an indentation 19 therein. A second conductor 20 of very thin pliable steel, or 85 any other suitable material, is also connected to the lower portion of the contact member 11, and the two conductors are secured, at their upper ends, to the base member 10 by the bolt 17 and the nut 17^a. A relatively 90 stiff metal strip 21, having a bearing point 22 at one of its ends, is secured, at its other end, to the base member 10 and is adapted to bear upon the conductor 20. A second relatively stiff strip 23 is secured, at its 95 upper end, to the opposite side of the base member 10 to that to which the strip 21 is secured, and its lower end is adapted to extend within the cut-away portion of the contact member 11 and to engage the conductor 18 at a point substantially opposite to the point that is engaged by the bearing point 22.

The stationary auxiliary contact member 12 is supported by a substantially U-shaped member 24 that is also secured to the base member 10 by the bolt 17. The contact member 12 is normally held in its lowermost position by a spring 25 and is electrically connected to a clip terminal 27 by a 110

flexible conductor 26. The terminal 27 is also secured to the base member 10 by the bolt 17 and the nut 17^a.

From the foregoing, it will be readily understood that the single bolt 17 and the nut 17^a secure the various alining and tensioning devices of the stationary contact members to the base member, and the base member is secured to a rod that may be adjusted vertically to any desired position by the turning of the nuts 13 and 14.

The rod 8 is slotted, at its upper end, to receive a clip terminal 28, and a bolt 29 and a nut 30 are provided for securing the clip terminal 28 in position.

The insulator 9 is provided with an annular flange or projection 31 between its respective ends, and the base plate or frame 1 of the circuit interrupter is provided with openings 33 having beveled under edges. An elliptically-shaped member 34 having a flanged outer rim is provided with three openings 35, 36 and 37. The openings 35 and 37 are adapted to register with openings 38 in the base plate or frame 1, and are adapted to receive bolts 39 that are provided with nuts 40 for securing the insulator 9 in position. Around the upper edge of the projection 31 is disposed a washer 41 and a substantially ring-shaped member 42 that is adapted to engage the beveled edges of the base plate or frame 1. The insulator 9 may be adjusted horizontally to secure accurate alinement of the contact members by adjusting the nuts 40. That is, the coöperation of the ring-shaped members 42 and the beveled edges constitute a universal joint or connection that permits of free adjustment of the switch members 2.

When the circuit interrupter is open, the conductor 18 rests against the lower end of the bearing strip 23, and the bearing point 22 exerts an initial pressure thereon. The contact member 11 assumes a position that is in direct alinement with the movable contact member 5. When the movable contact member 5 is moved upwardly, it engages the contact member 11 and distributes its force in such direction that its main component is in a line normal to the contact planes and passing through the bearing point 22, thereby precluding the undue straining of the alining strip 20 because the bearing strip 21 is provided for dissipating the external forces.

I do not limit my invention to the particular structure illustrated, as it may be variously modified without departing from the spirit and scope of the invention as set forth in the appended claims.

I claim as my invention:

1. A terminal member for a circuit interrupter comprising an insulator, a rod disposed within the insulator, contact members mounted on one end of the rod and nuts for

coöperating with the rod to adjust the position of the same with respect to the insulator.

2. A terminal member for a circuit interrupter comprising an insulator, a rod disposed within the insulator, contact members mounted on one end of the rod, and nuts for coöperating with the rod to adjust the position of the same and to clamp it in any desired position with respect to the insulator. 75

3. A terminal member comprising an insulator having an opening therethrough, a rod disposed in the opening in the insulator, a contact member mounted on one end of the rod and nuts for coöperating with the 80 rod to adjust the same longitudinally with respect to the insulator.

4. A terminal member comprising an insulator having an opening therethrough, a rod disposed in the opening in the insulator, a contact member mounted on one end of the rod, and nuts for adjusting the rod longitudinally with respect to and for clamping the same to the insulator. 85

5. In a circuit interrupter, the combination with stationary and movable contact members, of an insulator for the stationary members, means for adjusting the vertical position of the stationary members with respect to the insulator, and means for adjusting the horizontal position of the insulator with respect to the movable contact members. 90

6. In a circuit interrupter, the combination with an insulating member, a rod projecting therethrough and a contact member mounted on the rod, of means for adjusting the position of the rod with respect to the insulator and for adjusting the horizontal position of the insulator. 100

7. In a circuit interrupter, the combination with movable and stationary contact members, of insulators for the stationary contact members, and a universal connection for adjusting the positions of the insulators 110 with respect to each other.

8. A terminal member comprising an insulator, a rod disposed therein having screw threads thereon at each end, a contact member mounted at one end, and nuts for coöperating with the insulator and the screw-threaded portions of the rod for adjusting the same with respect to the insulator. 115

9. A terminal member comprising an insulator, a rod disposed therein having screw threads thereon at each end, a contact member mounted at one end, and nuts for coöperating with the insulator and the screw-threaded portions of the rod for adjusting the same with respect to and for securing 120 the same to the insulator.

10. In a circuit interrupter, the combination with stationary and movable contact members, of an insulator for the stationary members, means for adjusting the vertical 125

position of the stationary members with respect to the insulator, and means for adjusting the position of the insulator with respect to the movable members.

5. 11. In a circuit interrupter, the combination with movable and stationary contact members, of an insulator for the stationary contact member, means for adjusting the position of the stationary contact member with respect to the insulator, and a universal connection for adjusting the position of the insulator with respect to the movable contact member.

10. 12. In a circuit interrupter, the combination with movable and stationary contact members, of an insulator for the stationary contact member, means for adjusting the

position of the stationary contact member with respect to the insulator, and a universal connection for adjusting the horizontal position of the insulator with respect to the movable contact member. 20

13. A terminal member comprising an insulator having an opening therethrough, a screw-threaded rod disposed therein and having a contact member mounted on one end thereof, and nuts coöperating with the ends of the insulator and the rod for adjusting the same with respect to the insulator. 25

In testimony whereof, I have hereunto 30
subscribed my name this 28th day of Dec.
1915.

JOSEPH N. MAHONEY.
